UNITED STATES PATENT OFFICE.

JOHN E. MITCHELL, OF ST. LOUIS, MISSOURI.

BOLL-BREAKING AND COTTON-SEPARATING MACHINE.

1,322,927.

Specification of Letters Patent. Patented Nov. 25, 1919.

Application filed May 10, 1918. Serial No. 233,663.

To all whom it may concern:

Be it known that I, JOHN E. MITCHELL, a citizen of the United States, residing in the city of St. Louis and State of Missouri, have 5 invented new and useful Improvements in Boll-Breaking and Cotton-Separating Machines, of which the following is a specification.

This invention relates to boll breaking and cotton separating machines, and has for its general object to provide a simple and efficient arrangement and coördination of mechanism, whereby the cotton and hulls may be separated from each other with 15 greater rapidity and efficiency than has heretofore characterized machines of this type patented to me and which are now in extensive commercial use.

To appreciate more fully, the principle 20 of operation underlying the present invention, it is important to keep in mind the fact that there is considerable difference in the toughness or brittleness of the boll hulls fed into the breaking chamber, and also as much 25 difference in the sizes of the individual locks or wads of cotton, and in the character of the fiber of the cotton. The difference in the toughness of the bolls makes it necessary for the beaters in the breaking 30 chamber to act more on some than on others, in order to break the hulls apart. The difference in the size of the locks or wads of cotton, and in the character of the fiber of the cotton contained in the bolls, makes 35 quite a difference in the way the saw teeth take hold of the same. In the case of a small hard wad or lock of cotton, the kicker roll knocks it off of the saw teeth, the action of the kicker roll in this respect being similar 40 to its action in knocking back hulls carried up by the saws with the cotton. As will be developed more fully later on, my present invention is designed to secure high efficiency in operation notwithstanding the adverse 45 conditions arising from lack of uniformity in the product treated in the particulars above noted.

In addition to the high efficiency secured, my present machine also possesses a fewer 50 number of parts and is smaller in size, and hence more economical to build and operate than any of the prior machines of my invention.

In all such prior machines, and I should also include in this category machines and 55 improvements of Dennis Parks, either no means at all have been provided for repeated treatment in the breaking chamber of tough bolls, or of locks, or wads of cotton, which may not have been broken, or sufficiently 60 loosened up, respectively, in the breaking chamber; or else special mechanism has been provided for insuring the withdrawal of the cotton and hulls from the breaking chamber only after the bolls have been completely broken up, or the cotton locks and 65 wads sufficiently loosened up.

Examples of machines which provide for only one breaking operation on the bolls are shown for example in my prior Patents No. 70 1,030,913, dated July 2, 1912, and No. 1,129,220, dated February 23, 1915.

An example of a machine in which means are provided for repeated action of the beaters in the breaking chamber upon the 75 cotton and bolls, and for the positive withdrawal of the cotton and hulls from the breaking chamber only after the complete breaking up of the bolls and loosening up 80 of the cotton locks and wads has been effected is shown in the pending application of Dennis Parks, Serial No. 223,184, filed March 18, 1918.

In the former class of machines, there is 85 always present the liability of tough, unbroken bolls and wads or locks of cotton, neither of which can be engaged by the teeth of the saws, accumulating in the working chamber and clogging up the machine.

In the latter, or Parks type of machine, 90 while there is a vast improvement in the direction of uniformly breaking up the bolls and loosening up the cotton wads or locks, the complete loosening up of all of the wads 95 and locks of cotton is not assured, so that there is still present the liability to clog the working chamber above referred to, although in diminished proportion; and in the withdrawal of the cotton and hulls from the breaking chamber by the picker roll, 100 there ensues more or less crushing of the hulls between the blades of the picker roll and the gate or valve which controls the size of the opening through which the cotton and hulls are drawn by the picker roll. 105 Such crushing of the hulls makes it more

difficult to secure a complete separation between them and the cotton as will be readily understood.

In neither type of machine above referred to is any provision made for the return of any unbroken bolls, or of any of the hard locks or wads of cotton after they have once passed from the breaking chamber into the working chamber, in which latter the operation of separating the cotton from the hulls occurs.

Thus, in all such prior machines, whatever the character of the mixed product discharged into the working chamber to be 15 acted upon by the separating mechanism, it was substantially necessary to deal with the product as such, and, as above indicated, no means was provided for returning to the breaking chamber any part of such product 20 which was not in the proper condition to be acted upon by the separating mechanism.

While the disadvantages in operation incident to the prior commercial machines above referred to are only relatively serious, as machines of this type are well recognized commercial successes, being, in fact, so far as I am aware, the only machines of this character in general use; still, any improvement which will insure a more perfect separation of the cotton and hulls, and the recovery of a larger amount of the cotton, is of great importance, as it insures the operator a higher price for the cotton owing to its clean condition, and a greater return at a 35 stated price, owing to the increase in the yield of cotton.

Having in mind the objections to be overcome and the objects to be attained in the cleaning and separation of cotton, as above 40 set forth, my present invention is characterized by the facts that the boll breaking chamber is in direct, operative communication with the working chamber, the boll breaker, kicker roll, and saw cylinder are so 45 arranged and relatively disposed, that the saw cylinder is in the range and line of throw of the breaking cylinder, the breaking cylinder is in the range and line of throw of the kicker roll and the saw cylinder, and 50 that the working chamber affords a common zone of operation for these parts.

Under such an arrangement, unbroken bolls, or hard wads or locks of cotton, thrown into the working chamber by the breaking 55 cylinder, will be knocked back into the breaking chamber for further treatment either by the kicker roll or the saw cylinder. On the other hand, the wads or locks of cotton, after further treatment, will be thrown 60 by the breaking cylinder with considerable force against the saw cylinder, which action will tend to facilitate the engagement of the teeth of the saws with said locks or wads of cotton; so that, even though the latter may 65 not have been entirely loosened up by the

beaters of the breaking cylinder, they may in their partially reduced condition, be engaged by the saw teeth and be completely loosened up by the co-operative action of the saw cylinder and kicker roll.

The importance of having the opposed working sides of the saw cylinder and breaking cylinder move in opposite directions will be at once apparent, as otherwise the reciprocal action between these two parts would not be possible. A great advantage results from having the breaking cylinder positioned and rotating in a direction to throw the wads or locks of cotton against the teeth of the saws, for the purpose of forcing by impact the cotton against the points of the saw teeth, as this eliminates the necessity of the kicker roll returning small wads or locks of cotton to the breaking chamber to be opened out as often as would be necessary if such wads or locks were not driven with so much force against the teeth of the saws. The force of impact by which the cotton is thus made to adhere to the teeth of the saws is, of course, not sufficient to cause the hulls 90 to stick to the teeth of the saws, and the latter are free to fall through the outlet opening provided for that purpose if, or when, freed from cotton.

Such an arrangement and operation of 95 parts insures that there shall be no choking up of the machine, for the reason that the unbroken bolls and the hard wads or locks of cotton cannot remain in the working chamber, but, in the operation of the machine, they will be knocked either by the kicker roll or the saw cylinder, back into the breaking chamber for further action by the breaking cylinder.

The accompanying drawings illustrate the 105 best embodiment of the invention now known to me.

In said drawings:

Figure 1 is a view in side elevation of a machine constructed according to my invention, and

Fig. 2 is a central vertical sectional view, looking from the opposite side of the machine to that shown in Fig. 1.

Referring now to these drawings, the 115 numeral 1 indicates, generally, the casing of the machine, and 2, a hopper provided at the top thereof, in which are rotatably mounted feed rolls 3. Located immediately below the feed rolls 3, and communicating 120 with the interior of the hopper 2, is a circular breaking chamber 4, the bottom portion of which is in the form of a sieve 5, in which breaking chamber is rotatably mounted a boll-breaker 6, comprising a cylinder 7 125 provided on opposite sides with a row of pivoted beaters 8.

At the upper forward side of the breaking chamber there is provided a transverse shoulder or ledge 8^a, against which the bolls 130

will be thrown by the beaters 8, which action tends to assist breaking them up. However, the action of the beaters 8 is largely that of impact with the bolls, and the breaking action is not confined to throwing the bolls against the shoulder 8^a. Such action is merely assisted by this shoulder, which so to speak, acts as a stationary breaker. The breaking chamber 4 is provided on its inner side with an opening 9 which is in direct communication with a space 10 substantially inclosed on three sides by a saw cylinder 11, a kicker roll 12, and a valve 13. The space 10 is adapted to receive cotton and hulls from the breaking chamber 4 to be subjected to the separating action of the saw cylinder and kicker roll, and is hereinafter referred to as the working chamber. The valve 13 may be in the form of a board, and is mounted at its upper end on a bar 14 which is pivotally mounted at its ends in the end walls of the machine, and is adapted to be turned through the medium of a crank-arm 15 and a rod 16 connected to the lower end thereof and passing through the front of the machine, to adjust the valve toward and from the saw cylinder, whereby to regulate the size of an outlet 17, communicating with the working chamber 10 and providing a means of escape for hulls therefrom. The numeral 18 indicates a doffer brush for removing cotton from the saw cylinder, said brush revolving within a casing 19, part of which is in the form of a sieve 20. The sieves 5 and 20, as is well understood, permit a certain amount of refuse and dirt to be separated from the cotton. The numeral 21 indicates a conveyer mounted in a trough 22 at the bottom of the machine, into which latter the hulls fall after passing through the outlet 17 and are discharged by said conveyer through an opening 23.

It will be seen from an inspection of the drawing that the boll breaker and saw cylinder are located opposite each other, that there is a free or uninterrupted space between them, which space communicates with the breaking chamber 4 through the opening 9, and that the said space is substantially inclosed, or confined, by the working sides of the boll breaker 6, the kicker roll 12, the saw cylinder 11 and the valve 13. As indicated by the arrows, the boll breaker, kicker roll and saw cylinder all rotate in the same direction, so that their opposing faces move in opposite directions to each other.

Further, the positions of the saw cylinder and kicker roll relative to the breaking cylinder and chamber, and the distance separating these parts, are such that unbroken bolls, and hard wads or locks of cotton, may readily be knocked by the kicker roll or the saw cylinder into the breaking chamber; while, on the other hand, pieces of hull may be practically thrown through the outlet 17

by the beaters, and wads or locks of cotton be thrown by said beaters with considerable force against the saw cylinder. Driving mechanism for rotating the feed rolls 3 is not shown, as such operation may be performed in the usual or any desired way. The preferred form of driving the remaining elements of the machine is illustrated in Fig. 1, and will be briefly described.

A driving pulley (not shown) is mounted 75 on the shaft 24 of the doffer roll. On one end of this shaft is a pinion 25 which is in mesh with a gear 26 on one end of the shaft 27 of the saw cylinder. The shafts 28 of the kicker roll, 29 of the boll breaker, and 30 of 80 the conveyer 21, are each provided on one end with a pulley, indicated, respectively, by the numerals 31, 32, and 33. A belt tightening pulley 34 is mounted on a stub shaft 35. Over the pulleys named passes 85 an endless belt 36, having in its various laps the directions of movement indicated by the arrows. As will be seen, the saw cylinder is rotated by the gear connection 25, 26, and the other rotatable members are driven by 90 means of the belt and pulley arrangement described.

In the operation of the machine, when the material is fed into the breaking chamber by the feed rolls 3, the bolls that are brittle enough are instantly broken, or opened up by the action of the beaters 8, the cotton contained in the same released, and the hulls separated from each other; so that, when the mixed hulls and cotton are thrown 100 through the opening 9 into the working chamber 10, the hulls may at once fall through the opening 17, or be thrown through said opening by the impact of the beaters 8, and the released cotton be engaged 105 by the saw teeth and carried through underneath the kicker roll to be removed from the saws by the doffer brush, whence it passes to the gin.

In case any particular lock or wad of 110 cotton, when disengaged from the hulls by the beaters, has not been opened out or loosened up enough so that the saw teeth can thoroughly engage it, the kicker roll operates to knock it back into the breaking 115 chamber, where it is again carried around by the beaters and more thoroughly loosened up, and then thrown by the beaters against the saw teeth. If this operation has not resulted in loosening up the lock sufficiently 120 for it to be engaged by the saw, the operation just described is repeated until the teeth of the saws can get sufficient hold on the cotton to carry it through underneath the kicker roll, where hulls and tight wads 125 of cotton can not pass.

I claim:—

1. In a machine of the class described, a rotary boll breaker, a saw cylinder and a kicker roll surrounding in part a working 130

chamber for receiving the cotton and hulls, said chamber providing a common zone of operation for said breaker, cylinder and roll, and an outlet for hulls leading past said saw cylinder and communicating with said chamber.

2. In a machine of the class described, a rotary boll breaker, a saw cylinder and a kicker roll surrounding in part a working chamber for receiving the cotton and hulls, said chamber providing a common zone of operation for said breaker, cylinder and roll, and a valve defining, with said saw cylinder, the size of an outlet for hulls from said chamber.

3. In a machine of the class described, a rotary boll breaker, a saw cylinder and a kicker roll surrounding in part a working chamber for receiving the cotton and hulls, said chamber providing a common zone of operation for said breaker, cylinder and roll, and an adjustable valve defining, with said saw cylinder, the size of an outlet communicating with said chamber and providing a way of escape for hulls therefrom.

4. In a machine of the class described, a breaking chamber, a rotary boll breaker mounted therein, a saw cylinder, a kicker roll coöoperating therewith, said saw-cylinder and kicker roll forming in part the confines of a working chamber adapted to receive cotton and hulls and having working communication with said breaking chamber, whereby, in operation, the material treated may be thrown from one chamber into the other, and a valve defining with said saw cylinder the size of an outlet for hulls from said working chamber.

5. In a machine of the class described, a rotary boll-breaker, a saw cylinder and a kicker roll surrounding in part a common working chamber for receiving cotton and hulls, said boll-breaker and saw cylinder having their opposed sides rotating in opposite directions, and a valve defining with said saw cylinder the size of an outlet for hulls from said working chamber.

6. In a machine of the class described, a breaking chamber having an opening, a rotary boll-breaker mounted in said chamber, a saw-cylinder mounted with its working side facing said opening at a distance therefrom, and rotating in the opposite direction to the working side of said boll-breaker, a kicker roll located above and coöperating

with the saw cylinder, the construction providing a free clearance space between the boll-breaker and the saw cylinder and kicker roll, respectively, and a valve defining with said saw cylinder the size of an outlet communicating with said clearance space.

7. In a machine of the class described, a rotary boll breaker, a saw cylinder and a kicker roll surrounding in part a common working chamber for receiving cotton and hulls, said boll breaker and saw cylinder having their opposed sides rotating in opposite directions on opposite sides of said chamber and being in the range and line of throw of each other, and a valve defining with said saw cylinder the size of an outlet for hulls from said working chamber.

8. In a machine of the class described, a breaking chamber having an opening, a rotary boll breaker mounted in said chamber, a saw cylinder mounted with its working side facing said opening at a distance therefrom, and working in the opposite direction to the working side of said boll breaker, and a kicker roll located above and coöperating with the saw cylinder, the construction providing a free clearance space between the boll breaker and the saw cylinder and kicker roll, respectively, and said saw cylinder and breaking cylinder being in the range and line of throw of each other through said opening, and a valve defining with said saw cylinder the size of an outlet for hulls from said clearance space.

9. In a machine of the class described, a breaking chamber having an opening, a rotary boll breaker mounted in said chamber, a saw cylinder mounted with its working side facing said opening at a distance therefrom, and rotating in the opposite direction to the working side of said boll breaker, and a kicker roll located above and coöperating with the saw cylinder, the construction providing a free clearance space between the boll breaker and the saw cylinder and kicker roll, respectively, and said saw cylinder and kicker roll on the one hand, and the breaking cylinder on the other, being in the range and line of throw of each other through said opening, and a valve defining with said saw cylinder the size of an outlet for hulls from said clearance space.

In testimony whereof I have hereunto set my hand.

JOHN E. MITCHELL.
